TELESCOPE SIGHT MOUNT FOR FIREARMS

Leslie E. Whittemore, Dorchester, Mass.

Application September 25, 1948, Serial No. 51,140

7 Claims. (Cl. 42—1)

1

This invention relates to breech-loading top-ejecting firearms and particularly to firearms of this type that are equipped with a telescope sight.

Such telescope sight, when in operative position, is situated directly over the open top or ejection opening of the receiver through which the empty shells are ejected, and one of the objects of the present invention is to provide novel means by which when the bolt is moved backwardly into open position, the rear end of the telescope will be moved laterally to one side of the open top of the receiver so that it will not interfere with the ejection of the empty shells.

A further object of the invention is to provide novel means by which when the bolt is moved forward into closed position, it will automatically shift the position of the telescope sight from an inoperative position out of line with the open top or ejection opening of the receiver into an operative position.

A still further object of the invention is to provide novel means by which the telescope sight is locked in its operative position by the forward movement of the bolt.

In the present invention the front end of the telescope is pivoted to the barrel of the firearm and the movement of the telescope from its operative to its inoperative position and vice versa is accomplished by swinging the rear end of the telescope laterally about its pivot point, such swinging movement of the telescope being derived from the reciprocating motion of the bolt.

In the accompanying drawings, wherein I have shown a selected embodiment of my invention,

Fig. 1 is a top plan view of a portion of a shoulder arm having my improvements applied thereto and showing the telescope in operative position.

Fig. 2 is a fragmentary perspective view of the widened end portion of the rear supporting bracket.

Fig. 3 is a side view of Fig. 1.

Fig. 4 is a view similar to Fig. 1 but showing the telescope in its inoperative position.

Fig. 5 is a side view of Fig. 4.

Fig. 6 is a fragmentary plan view illustrating the rear end of the telescope in midway position.

Fig. 7 is a plan view of the bracket support for the rear end of the telescope.

Fig. 8 is a side view of Fig. 7.

Fig. 9 is a plan view of the cam track by which the telescope is given its swinging movement.

Fig. 10 is a side view of Fig. 9.

Fig. 11 is a perspective view of the clamping ring used for clamping the telescope to its supporting bracket.

Fig. 12 is a perspective view of the guiding member for the rear supporting bracket.

Fig. 13 is an enlarged sectional view on the line 13—13, Fig. 1.

2

In the drawing 1 indicates the stock or a shoulder arm, 2 indicates the barrel, 3 indicates the receiver which is provided with an open top for the ejection of the empty shells, and 4 is the usual bolt; these parts being such as are usually found in firearms of this type. The telescope sight is indicated at 5, and it may be of usual construction and is shown as provided with a removable eye piece 6.

10 In the present embodiment of the invention the front end of the telescope 5 is pivotally connected to the barrel 2 to permit the telescope to swing horizontally about its pivot to carry the rear end of the telescope from its operative position, in which it stands directly over the open top constituting the ejection opening of the receiver, to an inoperative position at one side of said ejection opening as shown in Fig. 4.

For thus pivotally mounting the telescope to the barrel, I have provided a front supporting bracket 7 which is clamped to the front end of the telescope 5 and is pivotally connected to a base member 8 that is secured to the barrel 2. The bracket 7 is provided with a hub portion 9 through which extends a pivot pin 10 that is screw threaded into the base 8, said pivot pin extending at right angles to the barrel. The bracket 7 is provided with a ring portion 11 in which the front end of the telescope 5 is received and said ring portion has extending therefrom a plurality of clamping jaws 12 which embrace the telescope 5. Said jaws are exteriorly screw threaded with a tapered thread, and cooperating with said jaws is an interiorly screw threaded ring 13 by which the jaws are clamped to the telescope 5. Because of the taper thread on the jaws 12, the screwing of the ring 13 to the right in Fig. 13 will clamp the jaws firmly to the telescope, while screwing the ring 13 to the left will release the clamping pressure of the jaws on the telescope.

The rear or eye piece end of the telescope has secured thereto a rear supporting bracket 14 which is clamped to the telescope in the same manner as the front supporting bracket 7, that is, said rear supporting bracket is provided with the ring portion 11 which encircles the telescope and is also provided with the clamping jaws 12 that have the taper screw thread on the exterior to receive the clamping ring 13.

50 The rear supporting bracket 14 is provided with a widened end portion 15 which rests on a guiding support 16 that is secured to the receiver. The member 16 is shown as having two side pieces 17 that overlie and are secured to the opposite sides of the receiver by suitable screws 18, and it is also provided with a bridge portion 19 on which the widened end 15 of the bracket 14 rests and slides. Said portion 15 is provided with the down-turned end 20 that overlies the edge 21 of the supporting member 16 and is also pro-

vided with the inturned lip 22 which fits underneath the edge portion 23 of the part 19. By this means the supporting bracket 14 is prevented from vertical movement, but is permitted lateral sliding movement on the bridge portion 19 as the telescope swings laterally about its pivot 10 in its movement from the operative position shown in Fig. 1 to the inoperative position shown in Fig. 4 and vice versa.

As stated above this swinging movement of the telescope is derived from the reciprocating movement of the bolt 4, and for this purpose the bolt has a cam member 24 secured to its upper face by means of screws 25, said cam member being provided with a cam rib 26 which is received in a notch 27 formed in the lip 22 of the rear supporting bracket. The cam rib 26 has a straight front portion 28, an intermediate cam portion 29, and a rear straight portion 30. When the bolt is in its forward or closed position shown in Figs. 1 and 3, the rear straight portion 30 of the cam rib 26 is occupying the notch 27 and the telescope 5 is thereby held in its operative position extending parallel to the barrel 12. When the bolt moves rearwardly, the cam portion 29 acting on the side walls of the notch 27 serves to shift the rear supporting bracket 14 laterally as shown in Fig. 4 thereby swinging the rear end of the telescope to one side of the receiver and uncovering the open top of the receiver for the ejection of the empty shell, such swinging movement of the telescope being about its pivotal axis.

The cam portion 29 is so disposed that it gives the rear end of the telescope its complete movement from operative to inoperative position during the first portion of the rearward travel of the bolt, and during the final rearward movement of the bolt, the straight portion 28 of the cam rib is operating in the notch 27.

The rear end of the telescope therefore, is moved into its inoperative position early enough during the rearward movement of the bolt so as to give plenty of time for the ejection of the empty shell.

Means are provided for automatically locking the telescope in its operative position during the final forward movement of the bolt. For this purpose the cam rib 26 is provided at its rear end with a locking lug 31, and the supporting member 16 as well as the widened part 15 of the rear supporting bracket 14 are provided with a locking notch to receive the locking lug 31. The notch in the supporting member 16 is indicated at 32 and that in the supporting bracket at 33. These notches are so disposed that they come into register with each other when the telescope is in its operative position, and hence during the final forward movement of the bolt, the locking lug 31 enters the two aligned notches 32, 33 thereby locking the telescope in its operative position.

I claim:

1. A breech-loading top-ejecting firearm having a barrel, a receiver having an ejection opening at the top for the ejection of empty shells, a reciprocating bolt, a telescope sight, means pivoting the telescopic sight at its front end to the barrel to swing laterally about a vertical axis between an operative position parallel to the barrel in which it is over said ejection opening and an inoperative position having an angular relation to the barrel in which it is at one side of said ejection opening, and means actuated by said bolt to give the telescope sight its swinging movement into both its operative and inoperative positions.

2. A breech-loading top-ejecting firearm having a barrel, a receiver having an ejection opening at the top for the ejection of empty shells, a reciprocating bolt, a telescope sight, means pivoting the telescopic sight at its front end to the barrel to swing laterally about a vertical axis between an operative position parallel to the barrel and with the rear end over said ejection opening and an inoperative position having an angular relation to the barrel and with its rear end at one side of said ejection opening, and means actuated by said bolt to give the telescope sight its swinging movement into both its operative and inoperative positions.

3. A breech-loading top-ejecting firearm having a barrel, a receiver having an ejection opening at the top for the ejection of empty shells, a reciprocating bolt, a telescope sight, means pivoting the telescopic sight at its front end to the barrel to swing laterally about a vertical axis between an operative position parallel to the barrel and with the rear end over said ejection opening and an inoperative position having an angular relation to the barrel and with its rear end at one side of said ejection opening, a supporting bracket secured to the rear end of the telescope sight, and a cam rib carried by the bolt and cooperating with said supporting bracket to swing the telescope sight about its pivot between its operative and inoperative positions.

4. A breech-loading top-ejecting firearm having a barrel, a receiver having an ejection opening at the top for the ejection of empty shells, a reciprocating bolt, a telescope sight, means pivoting the telescopic sight at its front end to the barrel to swing laterally about a vertical axis between an operative position parallel to the barrel and with the rear end over said ejection opening and an inoperative position having an angular relation to the barrel and with its rear end at one side of said ejection opening, a supporting bracket secured to the rear end of the telescope sight, a guiding support secured to the receiver and on which the supporting bracket rests for sliding movement, and a cam rib carried by the bolt and cooperating with the supporting bracket to swing the telescope sight about its pivot.

5. A breech-loading top-ejecting firearm having a barrel, a receiver having an ejection opening at the top for the ejection of empty shells, a reciprocating bolt, a telescope sight, means pivoting the telescopic sight at its front end to the barrel to swing laterally about a vertical axis between an operative position parallel to the barrel and with its rear end over said ejection opening and an inoperative position having an angular relation to the barrel and with its rear end at one side of said ejection opening, a supporting bracket secured to the rear end of the telescope sight, a guiding support secured to the receiver and on which the supporting bracket rests for sliding movement, and a cam rib carried by the bolt and cooperating with the supporting bracket to swing the telescope sight about its pivot, said supporting bracket and guiding support having inter-engaging portions which hold the swinging end of the telescope sight against vertical movement.

6. A breech-loading top-ejecting firearm having a barrel, a receiver having an ejection opening at the top for the ejection of empty shells, a reciprocating bolt, a telescope sight, means pivoting the telescopic sight at its front end to the barrel to swing laterally about a vertical axis between an operative position parallel to the barrel

and with the rear end over said ejection opening and an inoperative position having an angular relation to the barrel and with its rear end at one side of said ejection opening, a supporting bracket secured to the rear end of the telescope sight, a guiding support secured to the receiver and having an extended free edge, said supporting bracket having a lip engaging the underside of said free edge, said lip having a groove, and a cam rib carried by the bolt and operating in said groove whereby the telescope sight is swung about its pivot by the forward and backward movement of the bolt.

7. A breech-loading top-ejecting firearm having a barrel, a receiver having an ejection opening at the top for the ejection of empty shells, a reciprocating bolt, a telescope sight, means pivoting the telescopic sight at its front end to the barrel to swing laterally about a vertical axis between an operative position parallel to the barrel and with the rear end over said ejection opening and an inoperative position having an angular relation to the barrel and with its rear

end at one side of said ejection opening, a supporting bracket secured to the rear end of the telescope sight, a cam rib carried by the bolt and cooperating with said supporting bracket to swing the telescope sight about its pivot between its operative and inoperative positions, said supporting bracket having a locking notch, and a locking lug carried by the bolt and arranged to enter said locking notch when the bolt is in its forward position thereby to lock the telescope sight from swinging movement.
